Patented June 5, 1928.

UNITED STATES PATENT OFFICE.

EUGENE G. MASON, OF WASHINGTON, DISTRICT OF COLUMBIA, ASSIGNOR TO CONTINENTAL CAN COMPANY, INC., OF SYRACUSE, NEW YORK, A CORPORATION OF NEW YORK.

SEALED METAL CONTAINER.

Application filed March 25, 1924. Serial No. 701,721.

The invention relates to new and useful improvements in sealed metal containers, and more particularly to a metal container which may be readily opened by breaking 5 the sealing means therefor.

An object of the invention is to provide a sealing means for a metal container which includes an integral one-piece sealing ring extending all the way around the end of 10 the container to be closed, which sealing ring is provided with a series of breaking members arranged side by side and all the way around the container body and operating to release the entire sealing ring from 15 its gripping engagement with the container end and body portion of the container.

In the drawings—

Figure 1 is a plan view of a container having my improvement applied thereto;

Fig. 2 is a sectional view on the line $a-a$ of Fig. 1, showing an implement applied for lifting one of the breaking members;

Fig. 3 is a view similar to Fig. 2 but showing the breaking member as having been raised to a point where the sealing ring has been drawn across from its inner to its outer side;

Fig. 4 is a view similar to Fig. 1, but showing a slightly modified form of breaking member;

Fig. 5 is a view showing more or less diagrammatically, the manner of applying the sealing ring shown in Fig. 1 of the drawings, and

Fig. 6 is a view showing more or less diagrammatically and in section, the modified arrangement of the overlying flanges of the end and body portion of the container.

The present invention is an improvement 40 on the metal container shown and described in the application of Henry A. Fink, Serial No. 657,726, filed August 16, 1923, and is particularly directed to the construction of the sealing ring and the breaking members 45 thereof. The invention is shown as applied to a round container, and has a special advantage when used in connection with such a shaped container. The cylindrical body 1 of the container is provided with an out- 50 wardly projecting flange 2, which as shown in Figures 2 and 3, is substantially horizontal, while as shown in Fig. 6, it is rolled into a hollow roll. Other shapings of this flange may be used. The essential feature,

however, is that the flange shall be integral 55 with the body portion and shall project outwardly so that the sealing ring may be wrapped around underneath said flange for holding the container end on the container body. One end of the container body is 60 preferably closed by the usual method of double seaming, and this end is preferably applied by the packer to close the container after it has been filled. My improvement has to do with the attachment of the other 65 end of the container body in such a way that the user may be able to readily and quickly remove the sealing means which connects the end to the container body, so that the end can be removed and access had to the 70 contents of the containers. The container end is indicated at 3 in the drawings. Said container end as shown in the drawings is provided with a central depressed portion 4 which is adapted to frictionally fit within 75 the mouth of the container body so that said container end may be used as a friction cover for the container after the container has been opened. This central depressed portion of the container end forms a vertical 80 wall 5 which is the friction wall referred to.

At the upper end of the wall 5 there is an outwardly projecting integral flange 6 which is adapted to overlie the flange 2 on the container body. Between these flanges 2 85 and 6 there is preferably placed a sealing material 7 which may be of any suitable character.

After the container end has been placed on the container body, then a sealing ring 8 is 90 applied. Said sealing ring 8 is formed of one integral piece of metal and extends all the way around the top of the container. Said sealing ring has a horizontal portion 9 which overlies the flange 6 and a depend- 95 ing portion 10 which extends across the edges of the flanges 2 and 6. Said depend- ing portion 10 when first applied to the container extends some distance beneath the flange 2 as shown in Fig. 1, thus forming a 100 portion 11 which can be turned underneath the flange 2 as shown in Figures 2 and 3 of the drawings.

The sealing ring has an inwardly pro- 105 jecting portion 12 which is bent downwardly into a central depression in the container end. As shown in Figures 2 and 3, this vertical portion 12 extends substantially the

- full depth of the depression in the container end, although this is not essential to the invention. It is, however, essential that the portion 12 shown extends downwardly to some distance beneath the horizontal plane containing the flange 6 of the container end, so that the portions 9, 10, 11 and 12 of the sealing ring will, in a measure, form a housing for the flanges 2 and 6, and thereby 10 the flanges may be held in very tight sealing contact one with the other. The depending portion 12 of the sealing ring extends inwardly toward the center of the container to form a series of breaking members 13. 15 Each breaking member as clearly shown in Figures 1 and 4 of the drawings, is provided with an aperture 14 therethrough in which an implement for raising the breaking member can be inserted. As shown in 20 Fig. 1, the breaking members are placed side by side and extend all the way around the top of the container, but the adjacent edges are curved away from each other slightly, while in Fig. 4 of the drawings, 25 the adjacent edges of the breaking members are substantially in contact. The breaking members as shown in Fig. 4 are formed by radially cutting the metal as indicated at 15 in the drawings, and thus no 30 particular shaping of the breaking member is necessary. On the other hand, where the adjacent edges are curved as shown in Fig. 1, this forms plenty of clearance for the cutting out of the metal, and the metal can, 35 therefore, be readily cut to a point indicated at 16, which is well up to the vertical portion 12 of the sealing ring. By having this vertical portion 12 of the sealing ring extend over into the central depressed portion of the end, an anchorage is formed which 40 will hold the inner edge of the sealing ring, and allow the upper portion of the sealing ring to be drawn tightly around the flanges 2 and 6 and thus bring them into tight sealing contact. 45 When it is desired to remove the sealing ring so that access may be had to the container, an implement such as indicated diagrammatically at 17 in the drawings is 50 inserted through the aperture 14 and the inner end of the breaking member raised. The implement is then placed against the inner or shouldered edge of the sealing ring which serves as a fulcrum for the prying up 55 of the breaking member. Later, the implement may rest on the outer shouldered edge of the sealing ring as shown in Fig. 3 which forms a fulcrum whereby the sealing ring may be strained upon so as to tear the 60 metal from the point 18 to the point 19. Further strain upon this breaking member will tear the metal down the vertical portion 10 and across the underneath portion 11, thus completely rupturing the sealing ring.

This raising of the breaking member will

break the sealing ring usually at both sides of the breaking member and completely remove this section of the sealing ring. The other section of the sealing ring, will, however, still remain tightly grasping the flanges, in view of the fact that the inner portion 12 of the sealing ring extends over into the depressed portion in the container end, so that the ring, although severed, cannot be readily be moved laterally. Other 70 breaking members can be quickly raised, and thus each one in turn removed from the container, and by the lifting of these breaking members, the end entirely released from the container. This can be accomplished as will 75 be readily understood, by the implement 17, which may be the tine of a fork, a lead pencil, or any other similar article which 80 may be handy.

While I have shown the flanges as flat 85 in Figures 2 and 3 of the drawings, they may be rolled as shown in Fig. 6 of the drawings. The particular shaping of the flanges is immaterial to the present invention, which has to do particularly with the 90 construction of a series of breaking members extending all the way around so as to completely release the sealing ring from the flanges which are housed within said sealing ring. While I have shown the container end with a central depressed portion which 95 frictionally engages the inner wall of the container body, it will be understood also that said container end may have an in-turned horizontal flange with a depending 100 portion for frictionally engaging the inner wall of the container, but with such structure, it is essential that the portion of the end which spans and closes the opening in the container body, shall have a central depressed portion of sufficient extent at least, to insure that the sealing ring shall have a firm grip on the parts of the container end as well as the body portion of the 105 container. This avoids undue straining of the sealing ring during the closing of the container and enables a tighter seal to be made. 110

It is obvious that minor changes in the details of construction may be made without departing from the spirit of the invention as set forth in the appended claim. 115

Having thus described the invention, what I claim as new and desire to secure by Letters Patent is—

A sealed metal container comprising a cylindrical body portion having an outwardly extending flange, an end having a central depressed portion forming a vertical wall adapted to frictionally engage the 120 inner wall of the container body and a flange overlying the flange on the container body, an integral one-piece sealing ring having a portion overlying the flange on the container end and a portion projecting 125 130

downwardly along the inner face of the vertical wall on the container end and thence inwardly, said sealing ring having a portion projecting downwardly across the 5 outer edges of the flanges and adapted to be turned underneath the flange on the body portion for drawing the flange on the container end into tight sealing contact with the flange on the container body, said inwardly 10 projecting portion of the sealing ring operating to form an anchorage for holding the inner edge of the sealing ring so that the outer edge of the sealing ring may be drawn

tightly around the flanges, said inwardly projecting portion of the sealing ring being 15 formed into a series of breaking members located side by side of similar size and shape whereby said breaking members may be lifted one after another, and thus the entire sealing ring released from its gripping engagement on the container end and container body.

In testimony whereof, I affix my signature.

EUGENE G. MASON.
